UNITED STATES PATENT OFFICE.

ARTHUR S. WARNE, OF VANCOUVER, BRITISH COLUMBIA, CANADA.

CAMERA-SHUTTER RELEASE.

1,395,214.

Specification of Letters Patent. Patented Oct. 25, 1921.

Application filed July 21, 1919. Serial No. 312,328.

To all whom it may concern:

Be it known that I, ARTHUR S. WARNE, a subject of the King of Great Britain, residing at Vancouver, in the Province of British Columbia, Canada, have invented certain new and useful Improvements in a Camera-Shutter Release, of which the following is a specification.

This invention relates to an indicating counter for the shutter operating mechanism of a camera. The ordinary camera operator is liable to overlook rotation of the film before making another exposure, or if he does rotate the film he may do it subconsciously and has no means of ascertaining definitely that he has done so, unless he remembers the number of exposures he has taken, which should correspond with the exposure number of the film. As a consequence film developers will admit that a very large number of double exposures occur.

To overcome this difficulty, this invention is designed to indicate the number of shutter exposures, which number should correspond with the number on the film exposed.

The invention is particularly described in the following specification, reference being made to the drawings by which it is accompanied, in which:

30 Figure 1 is a longitudinal section to an enlarged scale showing the connection of the shutter operating plunger to the counter mechanism by which the movements of the plunger are indicated.

35 Fig. 2 is a longitudinal section of the counter casing and its nipple with its removable cap detached.

Fig. 3 is a side elevation of the indicating cylinder and its spring.

40 Fig. 4 is a plan of the upper face of the bottom of the same.

Figs. 5 and 6 show in plan and elevation the ratchet washer by which endwise movement of the stem partially rotates the indicating cylinder.

45 Figs. 7, 8 and 9 show in plan, vertical section, and side elevation the retaining check of the indicating cylinder, and the ratchet washer spring.

50 Fig. 10 is an alternative casing and nipple permitting one to swivel axially in relation to the other.

In these drawings 2 represents the flexible rod by which the shutter release is effected, 55 which rod is endwise movable in the flexible

tube 3 by pressing the plunger button 4 on the end of a stem 5 in which the end of the rod 2 is secured. This stem 5 is square in cross section and at 6 where it is connected to the rod 2 bears against a coil spring 7 which is within the tubular nipple 8 which receives the end of the flexible tube 3.

Secured on the outer end of this nipple 8 is a hollow cylindrical casing 9, in the wall of which is a circular viewing aperture 10. The open end of this cylinder is closable with a cap 11 through which the stem 5 axially passes the aperture fitting the square of the stem. Means is provided at 12 for insuring that the cap 11 fits on the casing in a definite position in relation to the square of the stem.

Within the cylindrical casing 9 is an indicating cylinder 13 which is relatively shorter than the casing and the edge of the open end of it is provided with V-shaped notches 14, corresponding to the number of exposures of the film. The closed end of this cylinder is apertured to pass freely onto the stem 5 without fitting its square and the inner face of the closed end has ratchet notches 15 impressed or otherwise formed in it, the number of which should be an even factor of the number of the serrations 14.

This cylinder 13 is held up against the underside of the cap 11 by a light spring 16 between its underside and the bottom end of the cylindrical casing 9. The square stem 5 adjacent its connection to the flexible rod 2 has a partial twist imparted to it, as at 17, the amount of twist being fully that fraction of a revolution corresponding to the number of exposures of the reel.

Resting on the notched face of the lower end of the indicating cylinder 13 is a washer nut 18 closely fitting the square of the stem 5, so as to be partially rotated back and forth by the twist of the stem as the stem is pressed downward through it and returns. This washer has its under face provided with ratchet notches 19 corresponding with those 15 of the cylinder 13. It is held in light engagement with the face 13 by a coil spring 20.

Just clear of the outer edge of the washer 18 so as to allow for the rise and fall of the washer over the ratchet notches, is a small hollow cylinder 21 from the upper side of which are diametrically opposed V shaped projections designed to fit between the serrations 14

of the indicating cylinder 13 as the same is rotated in one direction and prevent rotation backward. These projections 22 extend beyond the indicating cylinder 13 and fit into notches 23 provided in the upper edges of the cylindrical casing, by which the projections are retained against rotation. The lower edge of the cylindrical portion of this retaining check being in proximity to the 10 nut washer 18 prevents that washer canting and binding on the stem 5.

On the periphery of the indicating cylinder 13 are numbers from 1 to the number of film exposures for which the device is designed, which numbers, as the cylinder rotates, may be viewed successively through the aperture 10 of the casing 9.

In use, if the plunger 5 is pressed down against the resistance of the spring 7, to release the exposure shutter, the washer 18 is partially rotated by virtue of the twist 17 of the square stem 5 and, by virtue of the notches 19 of the nut washer engaging the notches 15 of the indicating cylinder, carries with it the indicating cylinder 13. As the indicating cylinder rotates its serrations 14 pass over the key projections 22 by which the cylinder is retained in the position to which it has been moved while the washer 18 returns during backward movement of the stem 5.

Although the device is apparently complicated in its number of parts, those parts are exceedingly simple to manufacture in quantity and are readily assembled, and the device is not liable to derangement.

It will be noticed that the friction of the twist 17 of the stem in the square hole of the nut washer 18 tends to press the indicating cylinder 13 downward against the light spring 16 which holds the notches 14 of that cylinder on the check detents 22, and the notched upper edge of the indicating cylinder is enabled to pass readily over the detents 22 without the exercise of much resistance against rotation. This in practice produces a smooth working but positive counter, for the spring 20 is in opposition to the spring 16, leaving only a slight preponderance of strength in the spring 16 tending to hold the notches 14 of the indicating cylinder on the check detents 22.

Again, by carrying the cylindrical portion 21 of the detents 22 downward toward the washer 18 to be just clear of it as it rises over the ratchet notches, that washer may be made relatively thin and the necessity of forming the square aperture to accord with the twist of the stem is avoided, which it would be necessary to do if the nut washer was thick enough to prevent it clutching the stem by canting slightly.

To enable the casing cylinder 9 to be turned on its axis to direct its viewing aperture 10 toward the operator, that cylinder

may be mounted to swivel axially on its connection to the nipple 8, somewhat as shown in Fig. 10.

The essential feature of the invention lies in the provision of an indicator on the shutter release mechanism which may be checked up with rotation of the film to provide for a fresh exposure. 70

Having now particularly described my invention, I hereby declare that what I claim 75 as new and desire to be protected in by Letters Patent, is:

1. A means for indicating, said means comprising the combination with a stem rectangular in cross section, said stem having a partial twist, a hollow casing provided with a viewing aperture through the cover of which casing said stem is endwise movable with provision preventing rotation of it in relation to the casing, an indicator cylinder 85 rotatably mounted within the casing and having around its periphery numbers corresponding to the number of exposures of the camera film, the upper edges of said cylinder having a corresponding number of notches 90 designed to engage a retaining detent projecting from the upper end of the casing and engaging projections across the upper face of the closed end of the cylinder, a spring tending to maintain the plunger 95 stem at the outer limit of its movement, a spring holding the notched upper edge of the indicating cylinder in engagement with the projections from the casing, a nut washer apertured to fit the endwise movable stem 100 and be partially rotated by its twist, said nut washer having ratchet projections corresponding in number to the indicating numbers of the cylinder and adapted to engage the projections in the closed end of the indicating cylinder, and a spring tending to hold the nut washer with its ratchet face in engagement with the radial projections of the indicating cylinder. 100

2. A means for indicating, said means 110 comprising a square stem, said stem having a partial twist, an apertured casing cylinder having a nipple secured to one closed end in axial alignment with the cylinder, said nipple having a passage into which the stem 115 release cable is adapted to pass, said nipple being chambered from the inner end to receive a coil spring between it and the end of the stem, a cover removably secured to the open end of the cylinder through which cover the stem is axially movable with provision preventing rotation therein, an indicating cylinder rotatably mounted within the casing, one end of which cylinder is provided with notches corresponding in number to the maximum number of indications for which the indicator is adapted, which notches engage projections in the upper end of the casing cylinder, and the opposite end ratchet engaging projections, a 130

spring holding the notches of the indicating casing, a nut washer fitting the square of the stem within the indicating cylinder and having ratchet teeth corresponding to the number of film exposures, and a spring holding the ratchet teeth of the nut washer in light engagement with the engaging projections of the indicating cylinder.

3. An indicating means comprising a stem 10 rectangular in cross section and having a partial twist, a hollow casing provided with a viewing aperture through the cover of which casing the plunger stem is endwise movable with provision preventing rotation 15 of it in relation to the casing, an indicating cylinder rotatably mounted within the casing, said cylinder having around its periphery numbers corresponding to the number of indications, the upper edge of said cylinder having a corresponding number of notches designed to engage a retaining 20 detent projecting from the inner upper end of the casing and engaging projections across the upper face of the closed end of the cylinder, a spring tending to maintain the plunger stem at the outer limit of its movement, a spring holding the notched upper edge of the indicating cylinder in engagement with the projections from the casing, a nut washer 25 apertured to fit the endwise movable stem and be partially rotated by its twist, said nut washer having ratchet projections corresponding in number to the indicating 30 numbers of the cylinder and adapted to engage the projections in the closed end of the indicating cylinder, and a spring tending to hold the nut washer with its ratchet face in engagement with the radial projections of the indicating cylinder.
- 40 4. An indicating means comprising a square stem having a partial twist, an apertured casing cylinder having a nipple se-

cured to one closed end in axial alinement with the cylinder through which nipple the flexible cable is endwise movable, said nipple 45 being chambered from the inner end to receive a coil spring between it and the end of the stem, a cover removably secured to the open end of the cylinder through which cover the stem is axially movable with provision for preventing rotation therein, an indicating cylinder rotatably mounted within the casing, one end of which cylinder is provided with notches corresponding in number to the maximum number of indications for which the device is adapted, which notches engage projections in the upper end of the casing cylinder, and the opposite end ratchet engaging projections, a spring holding the notches of the indicating cylinder in 50 light engagement with the projections of the casing, a nut washer fitting the square of the stem within the indicating cylinder and having ratchet teeth corresponding to the number of indications, and a spring holding 55 the ratchet teeth of the nut washer in light engagement with the engaging projections of the indicating cylinder.

5. An indicating means comprising a stem having a partial twist and a casing provided with a viewing aperture, a cover through which the stem is axially movable but not rotatable, an indicating cylinder rotatable within the casing, means co-operative with the twist of the stem for rotating the cylinder through a fraction of its circumference, a spring for forcing the stem in one direction, a member having a projection mounted in said casing, said indicating cylinder having notches to engage said projection, and a 60 spring for pressing said indicating cylinder against said projection.

In testimony whereof I affix my signature.
ARTHUR S. WARNE.
